UNITED STATES PATENT OFFICE.

LUDWIG HERMAN, OF UNION, NEW JERSEY, ASSIGNOR TO HIMSELF AND
JULIUS JONSON, OF NEW YORK, N. Y.

MAGNETO-ELECTRIC MACHINE.

SPECIFICATION forming part of Letters Patent No. 253,382, dated February 7, 1882.

Application filed May 13, 1880. (No model.)

To all whom it may concern:

Be it known that I, LUDWIG HERMAN, of Union, in the county of Union and State of New Jersey, have invented certain new and useful Improvements in Magneto-Electric Machines, of which the following is a specification.

The object of this invention is to furnish an improved magneto-electric machine for electric lighting, galvano-plastic, and other purposes, by which continuous currents of uniform direction may be produced. The same machine may also, without departing from its principle, be arranged as a dynamo-electric machine; also for furnishing currents of alternate directions, and, by reversing its action, as an electromotor.

The invention consists of a series of exterior electro-magnets, which are arranged in a circle around the axis of the machine, being provided with suitable pole-shoes at their ends, and, if desired, at one or more intermediate points. The helices of all these magnets are wound alike. The current is supplied from any source, and communicated to the magnets by means of central rings, radial springs, and transverse wire rods intermediately between the magnets. Within the exterior electro-magnets is arranged a central revolving armature, the core of which is made of a series of segments which are parallel to the axis and to the exterior electro-magnets. Around the segmental cores one or more continuous insulated wires are wound in the same direction throughout on one or both sides of the cores, according to the purpose for which the machine is to be employed. This revolving armature is supported on an eccentric middle portion of the shaft of the machine, so as to form a cylinder eccentric to and within a circle of the exterior magnets. The armature can be laterally adjusted on the shaft by means of conical bearings, and is adapted to revolve with the shaft and simultaneously around the same, as will more fully appear hereinafter.

In the accompanying drawings, Figure 1 represents a side elevation of my improved magneto-electric machine; Fig. 2, an end elevation, partly in vertical longitudinal section. Figs. 3 and 4 are respectively a detail section 50 and a side view of the rings and contact-pieces

for taking off the induced currents. Fig. 5 is a side elevation of the machine, taken on the opposite side to the former, partly in vertical transverse section. Figs. 6 and 6^a are detail views of the contact-rings and springs for supplying the exciting-currents to the machine; and Figs. 7, 8, and 9 are diagrams illustrating the disposition of the currents in the coils of the exterior electro-magnets in different relative positions of the contact-rings and radial springs.

Similar letters of reference indicate corresponding parts.

In the drawings, A represents the bed-plate, and A' the supporting side standards, of my improved magneto-electric machine. The standards A' carry in suitable bearings the revolving main shaft B. A second set of vertical standards, A², is arranged at right angles to the standards A', they supporting fixed ring-shaped frames A³. These ring-shaped frames A³ serve to support the outer electro-magnets, C, which are secured rigidly thereto. The electro-magnets C extend parallel to the shaft from ring to ring, and are wound with insulated wire in the same direction throughout, they being provided at the ends with poles of any desired shape. They may also be provided with intermediate poles, as shown in Fig. 2, in which case the winding of the coils 80 in the adjoining sections has to be in opposite direction, but continuously throughout all the sections of the exterior magnets.

The exciting-currents may be supplied to the outer series of electro-magnets from a separate magneto-electric machine, or from any other source of supply, the current being taken up by two metallic rings, a, which are fastened to the main shaft at one side of the machine and insulated therefrom and from each other in suitable manner, the rings having at diametrically-opposite points at their inner sides projecting cams a'. From these cams the current is transmitted to radial springs b, which are provided at their free inner ends with enlarged facings, which may be renewed from time to time when worn out. The outer ends of the springs b are attached to the insulated blocks b' between the electro-magnets C. The springs b are so disposed that before one leaves the 100

projection on the rings *a* the next adjoining spring touches thereon, as shown in Fig. 6^a, which is essential for the proper working of the machine. During each revolution of the 5 shaft the projections will form contact with the entire series of springs successively. The exciting-current is transmitted from the radial springs by connecting wire rods *d* to the electro-magnets *C*. The wire rods *d* pass through 10 the blocks *b'* from one ring-frame *A'* to the other intermediately between and parallel to the magnets *C*, as shown in Fig. 3. The current, in entering through any one of the radial springs *b*, is divided, as shown in Fig. 9, and 15 passes from the rod *d* in opposite direction through the coils of all the electro-magnets *C*, being united again on the diametrically-opposite rod and returned through the opposite spring and contact-ring to the source of supply. The result of this disposition of the current is that all the electro-magnets at one side of the springs will receive an opposite polarity to the remaining magnets on the other side of these springs. As soon as by the rotation of 20 the shaft the next springs are also brought in contact with the projections on the supply-rings a different disposition of the currents in the coils is produced, which is illustrated in Fig. 8. It will be noticed that in the helix of 25 the magnet between the springs in contact with the projections currents of opposite directions meet, which neutralize each other without exerting any influence upon the magnet, while in the remaining magnets exactly the same 30 polarities are produced as before. As soon as 35 the first set of springs leaves the projections on the rings the former disposition of the currents and of the polarities throughout all the electro-magnets takes place. By this arrangement 40 the magnet between said springs passes, while reversing its polarity, through a state of rest, which gives time to its molecules to arrange themselves, diminishing thereby the liability of the core to heating.

45 The shaft *B* is provided inside of its supporting-standards with an eccentric enlargement, *B'*, which carries the armature *D* by means of conical bearings *e*, screwed into the head of the same and properly fastened thereto 50 by jam-nuts or otherwise. The screw-connection of the heads with the bearings admits the proper lateral adjustment of the armature upon the shaft, so as to obtain the exact relative position of its poles to the poles of the outer electro-magnets. Upon the heads are supported a number of segmental magnets, *D'*, the pole-shoes of which are in line with poles of the 55 outer electro-magnets.

Around the segmental magnets *D'* of the 60 armature *D* is wound an induction-coil, which is formed of one or more continuous wires. The coil may be wound upon either or both sides of the cores, as required. When intermediate poles are used the coils of the armature have 65 to be wound in opposite directions to each other on the adjoining sections of the magnets. The eccentric middle portion of the shaft has

the effect that the poles of the revolving armature are not equidistant from the poles of the electro-magnets, but that they successively approach and recede from the same, according to the position of the eccentric portion in its rotation with the shaft. Owing to the eccentric position of the armature, the poles of one magnet of the armature will always pass very close 75 to the poles of one of the outer magnets, while all the remaining poles are at a gradually increasing distance from the poles of the remaining electro-magnets, until at the point opposite to that of greatest proximity the maximum intermediate distance between the poles is obtained.

To facilitate the revolving motion of the armature, I may provide the same with guide-tracks concentric to the outer circle of magnets. 85

To balance the weight of the eccentric armature, a counter-weight, *D''*, is secured to the shaft at a point diametrically opposite to the point of greatest eccentricity of the same, as shown in Fig. 2. The coils of the revolving armature are connected with their ends to rings *f*, which are supported on an insulated hub-shaped extension of the head of the armature at the side of the machine opposite to that where the radial springs are arranged. From 95 these rings the induced currents are taken off by means of contact-pieces *f'* and conducted to the line-wire in the usual manner. A continuous induced current of uniform direction is obtained by the action of the exterior electro-magnets upon the armature in the following manner: As the cams or projections of the contact-rings are in line with the diameter of the armature passing through its point of greatest eccentricity, the dividing-line between the inducing-magnets of opposite polarities will always correspond with the above diameter, even 105 while the machine is in motion. The rotation of the armature causes the passing or "rolling" of its poles along and past the faces of the exterior electro-magnets simultaneously with their approaching and receding from the same.

Assuming the machine at rest, the circuit of the armature closed and the exterior magnets excited, the latter will obtain opposite polarities at opposite sides of the diameter of greatest eccentricity. As soon as the shaft commences to revolve this diameter will progress with the same angular speed as all other parts thereon, forming always the dividing-line between the magnets of opposite polarity in the outer circle. At the same time the armature will, by means of its eccentric motion, approach the magnets of one polarity and recede from the magnets of opposite polarity. 115

It is a well-known fact that when a magnet approaches a closed conductor a current will be induced in the latter, which current has the same direction with a current produced in the conductor when the same is withdrawn from a magnet of opposite polarity. Consequently the currents set up in the armature during its motion by the action of the outer electro-magnets will be of the same direction, and as this 120

motion is a steady and continuous one so will the currents be steady and continuous. The center magnet may also be used by connecting the same with a source of electricity, as the inducing part, and generate currents in the outer magnets, using them as the armature—here the inducing magnet would be the moving part while the armature is at rest—leaving the whole construction as before, a steady current would flow through the helices, springs, center rings, and so on. By closing the circuit of each outer electro-magnet separately I obtain alternate currents in each magnet, which currents can be employed for the production of electric lights requiring alternating currents.

In using the machine as an electro-motor, the revolving armature as well as the exterior electro-magnets are excited by the same or separate currents. The action of the outer magnets having the same polarity as the armature will repel the latter, while the magnets of opposite polarity will attract the same, and the revolving armature, following the resultants of all these attractions and repulsions, will move toward the poles of opposite polarities. In so doing it will bring the next set of springs in contact with the projections of the supply-rings, continuing the rotary motion and causing the center shaft to revolve with a power proportioned to the strength of the current applied and to the size of the cores used.

It is obvious that the machine can also be used by interchanging the construction of the outer magnets with the inner magnets.

The electro-magnets may be made hollow and either a current of air or water passed through the same, so as to keep them cool, if desired.

In place of the segmental cores of the armature, a cylinder formed of permanent steel magnets whose poles of equal name would have to face the same way may be used.

The advantages of this construction are that by presenting the outer and inner magnets in their full length parallel to each other a larger percentage of induced currents is obtained. The currents, instead of being composed of a sum or succession of currents, as in the present well-known types of magneto-electric machines, will be of unbroken continuity while the inducing action upon the armature takes place. By making the eccentricity relatively small the entire motion of attraction and repulsion, as also induction, occur within the immediate neighborhood of the acting poles where the lines of force are most dense, and as magnetic and electric forces diminish in an inverse ratio of the square of the distance, it is self-evident that while the leverage will decrease in a direct algebraic ratio the power

will increase in proportion of the square thereof, showing a clear gain in making the eccentricity as small as practicable. By inserting a pole-changer of any appropriate construction into the circuit I can reverse the polarity of the current and magnets, and in this way reverse the motion of the motor, for instance. A further advantage is that magnets provided with intermediate poles will not retain any residual magnetism the moment the exciting current ceases.

Having thus described my invention, I claim as new and desire to secure by Letters Patent—

1. In a magneto-electric machine, the combination of fixed outer electro-magnets, an eccentric armature, springs *b* and *f*, revolving rings and cams, substantially as described.

2. In a magneto-electric machine, the combination of fixed outer electro-magnets, intervening insulated blocks, conducting-rods, radial springs, and an armature attached to an eccentric portion of main shaft revolving within the circle of the electro-magnets, substantially as described.

3. In a magneto-electric machine, the combination of a main shaft adapted to receive a laterally-adjustable eccentric armature, mechanism for transmitting currents, and a laterally-adjustable eccentrically-revolving armature, the field and armature magnets having end and intermediate poles, substantially as described.

4. In a magneto-electric machine, the combination of fixed outer electro-magnets having end and intermediate poles, an eccentric armature composed of segmental cores parallel with the axis, and a coil wound about said cores in the plane of rotation of said axis, substantially as described.

5. In a magneto-electric machine, a series of fixed exterior electro-magnets arranged in a circle with intermediate isolated blocks, radial springs attached thereto, and conducting-rods which pass through said blocks, in combination with a laterally-adjustable revolving armature, a main shaft which carries an eccentric and an eccentric armature which revolve within the circle of the magnets, contact-pieces, contact-rings, and cams attached to said shaft, which transmit the current to the radial springs, substantially as described.

In testimony that I claim the foregoing as my invention I have signed my name, in presence of two witnesses, this 12th day of May, 1880.

LUDWIG HERMAN.
